UNITED STATES PATENT OFFICE.

ALBERT M. BULLARD, OF CHICAGO, ILLINOIS, ASSIGNOR TO THE WESTERN ELECTRIC COMPANY, OF SAME PLACE.

APPARATUS FOR TELEPHONE-LINES.

SPECIFICATION forming part of Letters Patent No. 679,068, dated July 23, 1901.

Application filed June 7, 1899. Serial No. 719,642. (No model.)

To all whom it may concern:

Be it known that I, ALBERT M. BULLARD, a citizen of the United States, residing at Chicago, in the county of Cook and State of Illinois, have invented a certain new and useful Improvement in Apparatus for Telephone-Lines, (Case No. 2,) of which the following is a full, clear, concise, and exact description.

My invention relates to telephone toll-line apparatus and circuits, and has for its object to provide improved means whereby a telephone-line extending from a subscriber's station to a central office may be controlled either at the subscriber's station by the deposit of a coin or at the central office by the manipulation of certain mechanism there located independent of the coin-receiving apparatus at the subscriber's station—that is to say, it is the purpose of my invention to provide a telephone toll-line apparatus and circuits whereby the deposit of a coin by the subscriber is necessary in order to transmit a signal to the central station in initiating a call, but whereby the operator at the central office may signal the subscriber's station and may permit conversation to be had over the line without requiring the deposit of a coin.

In accordance with my invention the circuit of the telephone-line, while normally closed at the central office through a line-indicator, is normally open at the subscriber's station, two terminals being there provided for controlling the continuity of the talking and signaling circuit, between which terminals circuit may be completed in either of two ways—first, by the deposit of a coin in the coin-receiving toll-box, or, second, by means of a relay through which current may be directed from the central office. In the circuit with the relay I preferably include a coin-distributing electromagnet which may be operated from the central office to control the disposition of a coin which has been deposited by the subscriber—that is to say, if the connection desired by the subscriber can be obtained the coin, which he has previously deposited in order to complete the signaling-circuit through his line-indicator, is directed into the cash-box. Otherwise the coin may be directed into a return-chute leading to the outside of the box.

My invention will be more particularly described by reference to the accompanying drawing, which is a diagram illustrating by means of conventional symbols the several parts and circuit connections of the telephone toll-line and central-office apparatus of my invention.

The subscriber's station A is connected with the central office by means of the telephone-line a , having two branches a' a^2 , which terminate in the line-springs b' b^2 , respectively, of spring-jack b . The branch a' of the telephone-line is normally connected through a line-indicator c to ground by way of the back contact d' of the cut-off relay d . The branch a^2 of the telephone-line is likewise connected to ground through a battery or source of current e by way of the back contact d^2 of the cut-off relay.

At the subscriber's station the usual telephone apparatus for talking is located, the talking-circuit being controlled in part by the switch-hook f in the usual manner. A high-resistance polarized signal-bell g is permanently bridged across the telephone-line from a condenser g' . The telephone system illustrated is that known as the "common battery system"—that is, a system wherein the subscriber's transmitter is supplied with current from a centralized battery at the exchange office. This is well known and needs no further description.

There is a break z in the branch a' of the telephone-line at the subscriber's station, as indicated, and this break, if not closed, will prevent conversation being had over the line. It may, however, be closed in two ways, which I will presently describe—that is to say, first, through the front contact of the relay h , and, second, between the terminals i i by the deposit of a coin.

The helix of the relay-magnet h , whose armature controls through its front contact a bridge across the break z in the telephone-line, is permanently connected to ground from the side a' of the telephone-line through a retardation-coil and the helices of the polarized coin-distributing electromagnet l .

The tilting armature l' of the polarized magnet l is connected by means of the arm l^2 and link m with a swinging stop n , pivoted at n'

and normally maintained in a position to arrest the passage of a coin through the coin-chute *o*, wherein the coin-contacts *i i*, forming the terminals of the telephone-line *a'*, are located by a centralizing-spring *p*. The swinging valve *n* is adapted to be moved to one side or the other by the armature *l'* of the polarized electromagnet under the influence of positive or negative direct current which may be sent through the coils of said magnet, and so to release the coin and allow it to fall, guiding it either into the cash-box chute *q* or into the return-chute *r*, according to the direction in which the armature tilts.

At the central office a pair of connecting-plugs *tu* are provided, between whose tip and ring strands the centralized battery *v* is bridged through the usual repeating coil. The battery *v* is grounded at *v'*. Two keys *w x* are included in the tip and ring strands of the plug *u*, which keys are adapted when depressed to open the tip-strand and connect the ring-strand with a grounded source of positive direct current and a grounded source of negative direct current, respectively, through portions of the helix of the relay *y*, which controls a signal-lamp *y'*.

When the subscriber desires a connection, he first deposits a coin in the coin-chute *o*, which closes circuit between the contact-terminals *i i*, the coin resting upon the swinging stop *n*, which is, as before stated, normally in a central position. He then removes his telephone from its hook, thus providing a low-resistance path for the current through his telephone instruments, and current flows from grounded battery *e* by way of the back contact *d²* of the cut-off relay *d* out over the branch *a²* of the line through his instruments and back over the branch *a'* to ground by way of the back contact *d'* of the cut-off relay and the line-indicator *c*. This energizes the magnet of the line-indicator, which thereupon displays its signal and notifies the operator of subscriber A's desire for communication. The operator, perceiving the signal, inserts her answering-plug *u* into the spring-jack *b* of the telephone-line to make connection therewith. The operator is provided with the usual telephone and signaling apparatus associated with her plug and cord circuit in the usual manner and upon ascertaining the wants of the subscriber endeavors to connect his telephone-line with the one desired. If the connection can be obtained, she disposes of the coin which he has previously deposited by depressing the cash-box key *w*. This connects the branch *a'* of the line with a grounded source of positive direct current at a pressure of one hundred and ten volts, which current flows out over the line and to ground at the subscriber's station through the coils of the polarized magnet *l*. The magnet thereupon attracts its armature in a direction to swing the valve *n* in a contra-clockwise direction, releasing the coin and guiding it into the cash-

box chute *q*. If the connection desired cannot be obtained, however, the other or "return" key *x* is depressed, connecting the branch *a'* of the telephone-line with negative direct current at a pressure of one hundred and ten volts, which takes the same path as just described, but causes the polarized magnet to tilt its armature in the opposite direction, swinging the valve *n* to the left and guiding the coin into the return-chute *r*. Whichever key is depressed, the operator's signal-lamp *y'* is lighted to inform her that the grounded connection has been made through the coils of the polarized magnet at the subscriber's station and that the coin is properly disposed of. When one of the keys is depressed to dispose of a coin, the current flowing over the branch *a'* of the line energizes the high-resistance relay *h*, which thereupon attracts its armature and maintains the talking-circuit closed through its front contact. The armature of the relay is held in this position after the one-hundred-and-ten-volt current is removed from the line by twenty-four volt current flowing from the grounded centralized battery *v*. The polarized magnet is adjusted so as to be unaffected by twenty-four-volt current.

On incoming calls the subscriber is permitted to answer and talk without the deposit of a coin in the following manner: The relay *h* is adjusted to be operated by current at a pressure of twenty-four volts, which flows from the ground *v'* through the centralized battery *v*, out over side *a'* of the telephone-line, and to ground. The talking-circuit therefore is found to be closed at the front contact of the relay *h* as soon as the subscriber upon answering the ring at his signal-bell lifts his receiver from the hook.

Having thus described my invention, what I claim as new, and desire to secure by Letters Patent, is—

1. The combination with a telephone toll-line extending from a substation to a central office, of switch-contacts *i i* adapted to be closed by the subscriber, controlling a break in the telephone-circuit, a relay-magnet connected with the line at the substation in a branch circuit independent of said switch-contacts, a switch operated by said relay-magnet for closing said break controlled by the contacts *i i*, and means controllable from the central office for exciting said relay-magnet, whereby the central-office operator may close the break in the telephone-circuit at the substation independently of the switch-contacts operated by the subscriber, substantially as set forth.

2. The combination with a telephone toll-line extending from a substation to a central office, of switch-contacts *i i* adapted to be closed by the subscriber, controlling a break in the telephone-circuit, a battery and a signaling instrument in the line-circuit at the central office, said signaling instrument be-

- ing responsive to the flow of current in the circuit controlled by said switch-contacts, a relay connected with the line at the substation adapted when actuated to close the same 5 circuit which is controlled by the contacts *i i*, and means controlled in making connection with the line at the central office, for actuating said relay, whereby connection with the line at the central office dispenses with the 10 closure by the subscriber of the contacts *i i*, substantially as set forth.
3. The combination with a telephone-line extending from a subscriber's station to a central office, of switch-contacts at the subscriber's station adapted to be closed by the subscriber, for controlling the circuit through the telephone apparatus, and electromagnetic mechanism, controllable only from the central office, for completing the circuit through 15 the subscriber's telephone apparatus independently of said switch-contacts, substantially as set forth.
4. The combination with a telephone-line extending from a subscriber's station to a central office, the talking-circuit of said line being normally open at the subscriber's station, a relay connected with the telephone-line at the subscriber's station and adapted when actuated to close the talking-circuit of said 20 line, a spring-jack terminal for the line at the central office, a plug and its cord-circuit for making connection with said line by way of the spring-jack, and a source of current of suitable character to actuate said relay 25 connected with a contact and said plug, whereby the talking-circuit of the telephone-line is automatically closed by the insertion of the plug in the telephone-line spring-jack, substantially as set forth.
5. The combination with a telephone toll-line, of switch-contacts *i i* at the substation of the line, adapted to be closed by the subscriber, controlling the telephone talking apparatus, a relay connected with the line at 30 the substation, adapted to connect the telephone apparatus operatively with the line, and means, independent of the subscriber, 35 for operating said relay, substantially as set forth.
6. The combination with a telephone-line 40 extending from a subscriber's station to a central office, the talking-circuit of said telephone-line being normally open at the subscriber's station, a branch circuit at the subscriber's station including a relay and a polarized electromagnet, said relay being adapted when actuated to close the talking-circuit of the telephone-line, a signaling-circuit for said telephone-line including a line-indicator at the central office, and a switch at the substation for controlling said signaling-circuit, a plug and plug-circuit at the central office, and a spring-jack for the telephone-line in which said plug is adapted to be inserted to 45 make connection therewith, a source of current suitable for actuating said relay connected with one of the contact portions of the plug, whereby the talking-circuit of the telephone-line is automatically closed by the insertion of the plug in the spring-jack, said 50 polarized magnet being unresponsive to the current for operating said relay, and means at the central office for impressing upon the telephone-line suitable current for the actuation of said polarized magnet, substantially 55 as set forth.
7. The combination with a telephone-line 55 extending from a substation to a central office, said telephone-line being normally open at the subscriber's station, of a line-indicator at 60 the central office connected with the telephone-line, switch-contacts at the subscriber's station for controlling the circuit through said line-indicator, and means, controllable from the central office, for completing the 65 circuit of said telephone-line independently of said switch-contacts, substantially as set forth.

In witness whereof I hereunto subscribe my name this 18th day of May, A. D. 1899.

ALBERT M. BULLARD.
